Primary Examiner — David G Muller*Assistant Examiner* — Nathan M Johnston(74) *Attorney, Agent, or Firm* — Gwendoline Bruneau(57) **CLAIM**

The ornamental design for a kitchen bin holder, as shown and described.

DESCRIPTION

FIG. 1 is a perspective view of the kitchen bin holder showing our new design;

FIG. 2 is a front elevation view thereof;

FIG. 3 is a top plan view thereof;

FIG. 4 is a first side elevation view thereof;

FIG. 5 is a second side elevation view thereof;

FIG. 6 is a bottom plan view thereof; and,

FIG. 7 is a rear side elevation view thereof.

The design consists of the features of shape, pattern, configuration and ornamentation of the kitchen bin holder as shown in solid lines. The broken lines do not form part of the design.

1 Claim, 3 Drawing Sheets(56)
